(57) **CLAIM**

The ornamental design for a jewelry clasp, as shown and described.

DESCRIPTION

This application is related to the subject matter of concurrently filed U.S. utility patent application Ser. No. 14/524, 676, filed on Oct. 27, 2014, by Hines et al., and entitled “Clasps Having a Release Button and Jewelry Articles Employing Same”, the entire subject matter of which is incorporated herein by reference.

FIG. 1 is a perspective view of a jewelry clasp in accordance with the new design with a bracelet shown in an open position;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top view thereof;

FIG. 7 is a bottom view thereof;

FIG. 8 is a perspective view of the jewelry clasp with the bracelet shown in a closed position;

FIG. 9 is a front elevational view thereof;

FIG. 10 is a left side elevational view thereof;

FIG. 11 is a right side elevational view thereof;

FIG. 12 is a rear elevational view thereof;

FIG. 13 is a top view thereof; and,

FIG. 14 is a bottom view thereof.

The broken lines in the figures are for illustration purposes only and form no part of the claimed invention.

1 Claim, 10 Drawing Sheets
